UNITED STATES PATENT OFFICE.

ALFRED C. STAHFEST, OF NEW YORK, N. Y., ASSIGNOR TO EBERHARD FABER PENCIL COMPANY, A CORPORATION OF NEW YORK.

SHIPPING CASE AND DISPLAY STAND.

Application filed January 16, 1923. Serial No. 612,905.

To all whom it may concern:

Be it known that I, ALFRED C. STAHFEST, a citizen of the United States, and a resident of New York city, borough of Bronx, in the 5 State of New York, have invented new and useful Improvements in Shipping Cases and Display Stands, of which the following is a specification.

The primary object of this invention is to 10 provide a combined shipping case or package and display stand, particularly for pencils or the like, in which the articles may be enclosed for transportation or other purposes and displayed in an accessible position 15 when desired.

Another object is to provide such a device 20 constructed so as to provide storage space for reserve supplies of the articles being displayed.

Further objects are to provide a device of 25 the character described including a box having an open top and a bodily removable cover adapted to close said top, said cover being provided with means to support articles and said box and cover being formed with cooperating means to support said cover in a position at an angle to said box to display said articles; to thus provide such a device in which the box is formed in opposite 30 sides with grooves to receive the edges of said cover to support said cover edgewise in upright position intermediate the length of said sides whereby a reserve supply of said articles may be stored in said box behind 35 said cover which conceals them from view; to form the cover of such a device with pockets on its bottom side to support said articles so that said articles may be completely enclosed in the box by placing said cover 40 thereon, and displayed by merely raising the cover and setting it edgewise in the box, and to obtain other results and advantages as may be brought out by the following description.

Referring to the accompanying drawings, 45 in which the same characters of reference designate corresponding and like parts,

Figure 1 is a perspective view of a case and display stand constructed in accordance 50 with my invention shown in closed condition;

Figure 2 is a perspective view of the device with the cover in position to display the articles;

Figure 3 is a longitudinal sectional view,

on a reduced scale, through the case shown in closed condition;

Figure 4 is a transverse vertical sectional view taken on the line 4—4 of Figure 3;

Figure 5 is a view similar to Figure 4 60 with the cover arranged to display the articles, and

Figure 6 is an enlarged fragmentary sectional view taken on the line 6—6 of Figure 5.

In the specific embodiment of the invention shown on the drawings, the reference character A designates a box formed of suitable material, such as wood, and comprising a bottom 1, front side 2, rear side 3, 70 ends 4 and an open top 5. A cover B is provided to close said open top 5, said cover being shown as substantially flat and overlying the upper edges of the sides 2 and 3 and ends 4, as clearly shown in Figures 1, 3 75 and 4. Opposite sides of the box, in the present instance the ends 4, are formed on their inner sides with grooves 6 to slidably receive the end edges of the cover B to support the cover in a substantially upright 80 position within the box, as shown in Figures 2, 5 and 6. The grooves 6 are positioned adjacent the front side 2 of the box and are preferably inclined so that the cover is slightly inclined rearwardly when positioned 85 in said grooves.

The bottom side of the cover B is formed with a plurality of pockets 7 to support articles to be displayed, in the present instance pencils. Said pockets are shown as 90 formed of end pieces 8 which are of a size and so secured edgewise to the cover as to slip within the box when the cover is in closing position, as shown in Figures 3 and 4, a transversely extending piece 9 being secured to the outer edges of said end pieces 8 in spaced relation to the cover B, and partitions 10 similar in size and shape to the end pieces 8 being arranged intermediate said end pieces to provide the plurality of pockets. 95 The pockets are closed at one end by a strip 11 connecting the end pieces 8 at one end thereof. The piece 9 is of a width less than the length of the end pieces 8 so that the outer ends of the pockets are open and the articles made readily accessible for removal 100 from the pockets. Each of the pockets may be utilized to support a different kind of article.

For transportation or storage purposes, 110

the pockets 7 may be filled with the articles to be transported and the cover arranged over the open top 5 of the box as shown in Figure 1. The articles are thus completely enclosed within the box, and the end pieces 8 and strip 11 serve to prevent the cover from lateral movement on the box. When it is desired to display the articles the cover is lifted from the box and the end edges 10 slid into the grooves 6, whereby the cover is supported edgewise in a substantially upright position with the articles visible from the front side of the box and accessible for removal. The space between the cover and the rear side 3 of the box may then be utilized for storing a reserve supply of the articles, as indicated by dot and dash lines in Figures 2 and 5. It will be noted that the articles in the pockets 7 are always movable 15 with the cover B so that the articles may be enclosed within the box by merely slipping the cover from the grooves 6 and placing it over the open top 5 of the box, and displayed by merely raising the cover and setting it edgewise in the grooves 6 in the box. The cover thus has a number of functions, namely, supporting the articles, closing the box, and concealing the reserve 20 supply of articles within the box, and the box has a plural function in enclosing the articles, serving as a base for the cover when the same is in displaying position, and as a tray to receive the reserve supply of 25 articles.

Obviously, many changes may be made 30 in the detail construction of the box, compartments and cover without departing from the spirit or scope of the invention, and therefore I do not desire to be understood as limiting myself except as required by the 35 following claims when construed in the light of the prior art.

Having thus described the invention, what I claim is:

1. A device of the character described, 40 comprising a box having an open top, a bodily removable cover adapted to overlie the upper edges of said box to close said

open top, said box being provided on the inner sides of opposite side walls thereof with grooves to slidably receive the edges 50 of said cover to support the cover edgewise in upright position, and means on one side of said cover to support an article so that when said cover is in closing position said article is enclosed by said box and when said cover is in upright position said article is displayed.

2. A device of the character described, 55 comprising a box having an open top, a bodily removable cover adapted to overlie the upper edges of said box to close said open top, said box being provided on the inner sides of opposite side walls thereof with grooves to slidably receive the edges of said cover to support the cover edgewise in upright position, and means on one side of said cover to support an article so that when said cover is in closing position said article is enclosed by said box and when said cover is in upright position said article is displayed, 60 said article holding means engaging the inner sides of the side walls of said box when the cover is in closing position to prevent lateral displacement of the cover from the box.

3. A device of the character described, 65 comprising a box having an open top, a bodily removable cover adapted to overlie the upper edges of said box to close said open top, said box being provided on the inner sides of opposite side walls adjacent 70 one end thereof with grooves to slidably receive the edges of said cover to support the cover edgewise in upright position, and means on one side of said cover to support an article so that when said cover is in closing position said article is enclosed by said box and when said cover is in upright position said article is displayed, 75 said box forming a tray behind said cover when the same is in displaying position to receive a reserve supply of the article displayed and said cover concealing said reserve supply from view.

ALFRED C. STAHFEST.
